OF SYRACUSE, NEW YORK.

TYPE-WRITING MACHINE.

No. 926,149.

Specification of Letters Patent.

Patented June 29, 1909.

Application filed March 20, 1905. Serial No. 251,104.

To all whom it may concern:

Be it known that I, CHARLES E. TOMLINSON, citizen of the United States, and resident of Syracuse, in the county of Onondaga and State of New York, have invented certain new and useful Improvements in Type-Writing Machines, of which the following is a specification.

My invention relates to typewriting machines and it has for its principal object to provide an improved tabulator for such machines.

My invention consists in certain features of construction and combinations and arrangements of parts which will be fully described herein and particularly pointed out in the claims.

One embodiment of my invention is illustrated in the accompanying drawings, in which—

Figure 1 is a side view, partly in section, of a typewriting machine having my invention applied thereto; Fig. 2 is a top plan view of the key mechanism of my tabulator; Fig. 3 is a front view of the machine, partly in section; Figs. 4, 5 and 6 are similar top plan views of a portion of the mechanism, the parts being shown in different positions in the different views; Fig. 7 is a top view of a detail; Fig. 8 is a plan view of the rear part of the top plate of the machine with my tabulator mechanism in position; and Fig. 9 is a rear view of the same.

I have shown my invention applied to a Smith Premier typewriter, but said invention is also applicable to typewriters of other styles.

The base portion of the main frame of the machine shown in the drawings comprises side plates 1 connected together by a back plate 2. Posts 3, rising from said side plates, support a top plate 4 on which are mounted rails 5 which support a carriage 6 on which is mounted a platen 7. The carriage 6 is connected with the rails 5 by the ball bearing ordinarily employed in the Smith Premier machine. Type bars 8 are pivotally supported from the top plate 4 and are actuated by links 9, the lower ends of which are pivoted to arms 10 projecting from rock shafts 11 which are journaled at their rear ends in the back plate 2 and at their forward ends in angled frame plates 12. Keys 13 are mounted on the upper ends 55 of key stems 14 which extend through suit-

able openings in the frame plates 12 and at their lower ends are pivoted to arms 15 projecting from the rock shafts 11. Returning springs 16 are coiled about said rock shafts and are connected at one end with the frame plates 12 and at the other end with the arms 15. The rock shafts 11 have projecting therefrom near their rear ends, arms 17 (Fig. 3) which are adapted to engage lugs 18 on a universal bar or gate 19 which is supported by links 20 which are pivoted at one end to said universal bar and at the other end to the back plate 2. The construction is such that when any key is depressed its type bar will be thrown against the platen 70 and the universal bar or gate 19 will be moved to the right. Two lugs or ears 21, bent off from the universal bar 19, embrace a grooved roller 22 which is mounted on an arm 23 projecting from a vertical rock shaft 75 24 which is journaled at its lower end in the back plate 2 and at its upper end in the top plate 4 above which it is formed with or has mounted thereon a head or enlargement 25 to which the feed dogs are pivoted. The shaft 24 and its head or enlargement 25 constitute the dog rocker of the machine.

A space bar or key 26 is mounted on a stem 27 which extends downward through a frame plate 28 which is similar to the frame plates 12, but joins the extreme forward ends of the side plates 1. The stem 27 is pivoted at its lower end to an arm 29 projecting from a rock shaft 30 which is journaled at its forward end in the frame plate 28 and at its rear end in the back plate 2. The rock shaft 30 has a returning spring 31 similar to the returning springs 16 of the rock shafts 11. An arm 32, projecting from the rock shaft 30 near its rear end, stands in position to engage a pin 33 which projects from the front face of the gate 19. The construction is such that if the space key or bar be depressed the universal bar will be operated in the same manner as by one of the carriage keys. The space key 26 is elongated, as shown in Fig. 3, and extends part way across the keyboard in front of the keys 16. In order to better support and steady this elongated key an arm 34 is pivoted to the stem 27 at 35 some distance above the arm 29. Said arm 34 is pivoted on a shouldered and headed screw 36 which is threaded into the frame plate 28. To give the arm a better bearing on the screw 36, said arm is bent in the form indi- 110

cated in Figs. 1 and 3 so that it bears on the screw 36 at two points.

A feed rack 37 is mounted on the rear edge of the carriage and has rack teeth on the under side thereof. Said rack teeth mesh with a pinion 38 which is journaled on a stud projecting from an arm 39 which in turn projects from a sleeve 40 which surrounds a shaft 41, which is journaled in a housing 42 on the top plate 4. The shaft 41 has fixed on the forward end thereof a pinion 43 which meshes with the pinion 38, and said shaft has rigidly mounted on the rear end thereof an escapement wheel 44 which 10 coöperates with the feed dogs mounted on the head 25 of the shaft 24. Said feed dogs may be arranged for either the "ordinary" or "reverse" feed, but in the present case dogs adapted for the "ordinary" feed are 15 shown. A stepping dog 45 is pivoted on a pin 46 which is supported in ears 47 rising from the head 25. This dog is normally engaged by the escapement wheel 44, as shown in Figs. 4 and 8. A holding dog 48 is mounted 20 below the stepping dog 45 and, as best shown in Fig. 7, said dog is pivoted on a vertical pivot consisting of a shouldered and headed screw 49. Lying as this dog does between the two ears 47, it is substantially 25 mounted in a slot, the walls of which prevent rotation of the dog about its pivot in one direction, but said dog has a notch 50 (Fig. 7) in one side thereof and is cut away on the other side and a spring 51 is compressed between the dog and one of the ears 47. In 30 the ordinary operation of the machine this spring holds the dog in the position shown in Fig. 7 so that the dog 48 ordinarily acts as a fixed dog.

40 The carriage is drawn across the machine by a strap 52 which is connected at one end to a pin 53 depending from the carriage and at the other end to the usual spring drum 54.

45 The mechanism thus far described is or may be substantially like that ordinarily used in the Smith Premier machine, with the exception of the construction of the holding dog 48 and the mechanism is adapted to be used in the ordinary way for writing and feeding the carriage. The ordinary operation of the feed dogs is shown in Figs. 4 and 5, the former of which represents the parts in the position they occupy normally and the latter in the position they occupy 50 when one of the character keys or the space key is depressed. As shown in Fig. 4, the stepping dog 45 is normally engaged by a tooth of the escapement wheel 44 but when the space key or one of the character keys is 55 depressed the gate 19 is moved to the right and the shaft 24 and its head 25 are swung to the position shown in Fig. 5 when the tooth of the escapement wheel is held by the holding dog 48 and the stepping dog has its 60 operative end raised by a spring (not shown)

to engage the next succeeding tooth of the escapement wheel when the key is released. In this operation the holding dog 48 is pushed under the tooth of the escapement wheel by the spring 51.

70 My tabulator mechanism comprises a tabulator bar 55 which is mounted on arms 56 which are secured to the carriage 6 by screws 57 or in any suitable manner. The arms 56 extend upward and backward from their 75 point of connection with the carriage, as shown in Fig. 1. The tabulator bar 55 is or may be of rectangular cross section and is formed on its upper and lower sides with a series of notches or transverse grooves 58 80 spaced apart a distance equal to the letter space feed movement of the carriage. One or more stops 59 are mounted on the bar 55. As shown in the present case, these stops are made of sheet metal having an open ended 85 slot which fits over the tabulator bar 55 in one of the pairs of notches 58.

85 The denominational stops are disposed beneath the bar 55 and consist of the upper ends 60 of a series of vertically movable 90 bars 61 which are pivoted at their lower ends at 62 to the rear ends of a series of levers 63 which extend from front to back of the machine, beneath the rock shafts 11 and 30 and which are pivoted on a stationary frame rod 64, which is supported at its ends in the side plates 1 of the main frame. The vertically movable bars 61 come up behind the top plates 4, as shown in Figs. 1 and 9, and above said top plate they are 100 curved toward the front of the machine and the stop portions 60 of said bars extend slightly upward from said forwardly extending portions. The upper ends of these bars rest in slots formed in an upward extension 65 of the housing 42 and are spaced apart a letter space distance. Above the back plate 2 of the machine frame, the bars 61 are curved as shown in Fig. 1 so that the lower ends of said bars lie in front of said 110 frame plate 2. The rock shafts 11 are arranged in vertical tiers, and there is a wide space near the middle of the machine between two of these tiers. The bars 61 utilize this space, two of them being bent off as 115 shown in Fig. 3, to avoid interference with the rock shaft 30. The levers 63 are not parallel, but fan out, toward the front of the machine, so that their forward ends are a suitable distance apart. These forward ends of the levers 63 extend upward, as shown at 66, being guided by slots formed in the forward one of the frame plates 12, as indicated in Fig. 1. These upward extensions 66 of the levers 63 are bent off to 120 form lugs or ears 67 which stand just back of the space key or bar 26. A series of push keys 68 are slidably mounted in the space bar 26 and projecting from the forward edge or slide thereof into position to be pressed 125

toward the back of the machine by the finger or thumb of the operator. These keys and connections have the form shown in Fig. 1. A space or slot 69 is formed in the under side of the bar 26 and the keys 68 project through the forward wall of this slot. Within the slot 69 the stem of each key 68 is reduced and is surrounded by a coiled returning spring 70 which is compressed between the key 68 and the rear wall of the slot 69. The key stem extends through said rear wall and at its rear end is enlarged, as shown at 71. The shoulder formed by the enlargement 71 does not extend entirely into the slot 69 so that said shoulder serves to limit the forward motion of the key under the impulse of the spring 70. The construction is such that if any key 68 be pushed, the end 71 of said key will extend out over the corresponding lug 67. If then the space bar 26 be depressed, the corresponding lever 63 will be depressed at its forward end and the bar 61 pivoted to the rear end of said lever will be elevated, moving the stop 60 on said bar into the path of one of the column stops 59. The key corresponding to the hundreds denomination is shown in operative position in Fig. 2. The depression of the space key will also operate the universal bar 19, rotate the shaft 24 and move the stepping dog 45 out of engagement with the escapement wheel 44, but I have provided means to prevent the holding dog 48 from engaging the escapement wheel when the tabulator is operated. In this operation said dog is held in inoperative position, as shown in Fig. 3, with the result that the escapement wheel, and therefore the carriage is released from the step by step feed mechanism. In order to thus retain the holding dog out of engagement with the escapement wheel when the tabulator is operated, a dog 72 is pivoted on a screw 73 which is threaded into a bracket 74 (Fig. 8) which extends toward the back of the machine from the top plate 4. This dog normally stands in the position shown in Fig. 1, out of the path of the tail of the holding dog 48; but when any one of the bars 61 is elevated, said dog 72 is raised into position to arrest the holding dog 48, as shown in Fig. 6, and prevent said dog from turning with the shaft 24. In this operation the head 25 of said shaft turns, compressing the spring 51. In order to raise the dog 72 in the manner which has been described, said dog has rigidly connected thereto one end of a universal bar or bail 75, which extends through the lower ends of slots 76 (Fig. 1) in the bars 61. On the other side of the series of bars 61 from the dog 72, said bail is formed with an arm 77 and a pivot 78 which is pivoted in a bracket 79 projecting back from the top plate 4. When any bar 61 is lifted, the bail 75 is elevated, moving freely through the

slots 76 in the other bars 61 of the series. The upper ends of the bars 61 are held against transverse motion by the slots in the frame piece 65 and against motion in a front and back direction by the bail 75 working in the slots 76.

It will be perceived that my tabulator mechanism is operated by the ordinary space key of the machine. So far as I am aware this is broadly new. It will also be perceived that the carriage release is effected by modifying the ordinary step by step feed of the carriage, that is to say, that that dog which is normally in engagement with the escapement wheel is moved out of engagement with said escapement wheel in the ordinary manner, the carriage being released by preventing the holding dog from moving into engagement with the wheel. So far as I am aware this mode of operation is broadly new.

It will be obvious that various changes may be made in the details of construction and arrangement without departing from the spirit of my invention.

What I claim as new and desire to secure by Letters Patent, is:—

1. In a typewriting machine, the combination of a carriage; a tabulator mechanism; a space key; a step by step feed mechanism controlled by said space key; and hand actuated means operable at will to effect a connection between said space key and tabulating mechanism.

2. In a typewriting machine, the combination of a carriage; a tabulator mechanism comprising denomination stops and one or more column stops; a space key; a step by step feed mechanism controlled by said space key; and means whereby said space key may be connected with and may operate said tabulator mechanism.

3. In a typewriting machine, the combination of a carriage; a tabulator mechanism comprising denomination stops and one or more column stops; a space key; a step by step feed mechanism controlled by said space key; and means whereby said space key may be operatively connected with any one of said denomination stops.

4. In a typewriting machine, the combination of a carriage; a tabulator mechanism comprising one or more stops mounted on said carriage and a plurality of stops mounted on the main frame; a space key; a step by step feed mechanism controlled by said space key; and means whereby said space key may be operatively connected with any one of said stops mounted on the main frame.

5. In a typewriting machine, the combination of a carriage; a tabulator mechanism; a space key; a tabulator key; and means whereby said tabulator key when operated connects said space key with said tabulator mechanism.

6. In a typewriting machine, the combination of a carriage; a tabulator mechanism comprising a plurality of stops mounted on the main frame of the machine; a space key; a series of tabulator keys; and means whereby a tabulator key when operated connects said space key with the stop corresponding to said tabulator key. 70
7. In a typewriting machine, the combination of a carriage; one or more tabulator stops mounted on said carriage; a series of denomination stops mounted on the frame of the machine; a space key; a series of tabulator keys; and means whereby a tabulator key when operated connects said space key with one or another of said denomination stops. 75
8. In a typewriting machine, the combination of a carriage; a space key; a step by step feed mechanism controlled by said space key; a tabulator mechanism; and a tabulator key mounted on said space key and normally out of coöperation with said tabulator mechanism but movable to a position to coöperate with and to control said tabulator mechanism. 80
9. In a typewriting machine, the combination of a carriage; a space key; a step by step feed mechanism controlled by said space key; a tabulator mechanism comprising a plurality of stops; and a plurality of tabulator keys mounted on said space key and controlling said tabulator stops. 85
10. In a typewriting machine, the combination of a carriage; a space key; a step by step feed mechanism controlled by said space key; one or more column stops mounted on said carriage; a series of denomination stops mounted on the frame of the machine; 90 and a series of denomination tabulator keys mounted on said space key and controlling said denomination stops.
11. In a typewriting machine, the combination of a carriage; a space key; a step by step feed mechanism controlled by said space key; a tabulator mechanism comprising a plurality of stops; a plurality of operating devices for said stops, said operating devices having a part lying adjacent to said space key; and a plurality of denomination tabulator keys mounted on said space key and adapted to connect said space key with one or another of said operating devices. 95
12. In a typewriting machine, the combination of a carriage; a space key; a step by step feed mechanism controlled by said space key; a denominational tabulator mechanism comprising means for arresting the carriage at any denominational position in a column; and means whereby said space key may operate said denominational tabulator mechanism. 100
13. In a typewriting machine, the combination of a carriage; a space key; a step by step feed mechanism controlled by said 105
- space key; a tabulator mechanism comprising one or more column stops and a series of denomination stops; a series of tabulator keys mounted in said space key; and a series of levers each connected with a denomination stop; means whereby any tabulator key may connect said space key with the corresponding lever; and means controlled by said lever and by the space key for releasing the carriage. 110
14. In a typewriting machine, the combination of a carriage; a step by step feed device for said carriage; a space key for controlling said step by step feed device; a special key mounted on said space key; and a device coupled by said special key to said space key and adapted to release said carriage from said step by step feed device. 115
15. In a typewriting machine, the combination of a carriage; an escapement mechanism comprising an escapement rack and two dogs adapted alternately to move into position to arrest said rack; a dog rocker for moving said dogs; and means for preventing the movement of one of said dogs when the rocker is operated to move the other dog out of engagement with the rack, whereby the carriage may be released. 120
16. In a typewriting machine, the combination of a carriage; a step by step feed device for said carriage comprising an escapement rack and two dogs adapted to engage said rack alternately; printing keys and a space key adapted to operate said dogs, and means for holding one of said dogs against movement and out of engagement with said rack when the other of said dogs is moved by said space key out of engagement with said rack. 125
17. In a typewriting machine, the combination of a carriage; a step-by-step feed device for said carriage comprising an escapement rack and two dogs adapted to be moved alternately into engagement with said rack; a space key for controlling said dogs; a special key mounted on said space key; and means controlled by said special key for locking one of said dogs when the other dog is moved by said space key out of engagement with said rack. 130
18. In a typewriting machine, the combination of a carriage; a step by step feed device for said carriage comprising an escapement rack and two dogs; a dog rocker on which said dogs are mounted; means for rocking said dog rocker to afford a step by step feed to the carriage; and a special key and connections for preventing one of said dogs from engaging the rack when the other of said dogs is moved by the dog rocker out of engagement with said rack, whereby the carriage may be released. 135
19. In a typewriting machine, the combination of a carriage; a step by step feed device for said carriage; comprising an escape- 140

- ment rack and two dogs; means for moving said dogs in unison to cause them to engage said rack alternately to afford a step by step feed to the carriage; and a stop controlled by hand operated means for arresting one of said dogs when the other of said dogs is moved out of engagement with said rack.
20. In a typewriting machine, the combination of a carriage; a step by step feed mechanism for said carriage comprising an escapement rack and two dogs; a space key for operating said dogs to feed the carriage; a special key mounted on said space key; and a stop controlled by said special key for arresting one of said dogs when the other of said dogs is moved out of engagement with the rack by said space key.
21. In a typewriting machine, the combination of a carriage; an escapement rack for said carriage; a dog for coöperating with said rack; means including a spring for moving said dog into engagement with said rack; and a carriage release device including a stop adapted to arrest said pawl and prevent said spring from moving it into engagement with said rack.
22. In a typewriting machine, the combination of a carriage; an escapement wheel 44 geared to said carriage; a dog rocker 30 having two dogs 45 and 48 mounted thereon and adapted to be moved by said dog rocker into and out of engagement with said escapement wheel; a space key controlling said dog rocker; a key 68 mounted on said space key; a bar 61 controlled by said key 68; and a stop 72 controlled by said bar 61 and adapted to prevent said dog 48 from engaging said escapement wheel 44.
23. In a typewriting machine, the combination of a carriage; an escapement wheel geared to said carriage; a dog rocker having two dogs mounted thereon and adapted to be moved by said dog rocker into and out of engagement with said escapement wheel; a space key controlling said dog rocker; a tabulator key mounted on said space key; a tabulator bar controlled by said tabulator key; and a stop controlled by said tabulator bar and adapted to prevent one of said dogs from engaging said escapement wheel.
24. In a typewriting machine, the combination of a carriage; a step by step feed device for said carriage comprising an escapement rack and two dogs; a denominational tabulator comprising one or more tabulator stops and a series of denominational stops; a series of to and fro moving members for controlling said denominational stops; and a stop piece adapted to be moved by any one of said to and fro moving members into position to arrest one of said dogs and to prevent it from moving into engagement with said escapement wheel.
25. In a typewriting machine, the combination of a carriage; a denominational tabulator for said carriage comprising a tabulator bar mounted on said carriage; one or more column stops mounted on said tabulator bar; a series of denominational stops standing beneath said tabulator bar; a series of up and down reciprocatory bars, one for each denominational stop; and a series of levers extending from front to back of the machine and having said reciprocatory bars connected with their rear ends so that when the forward ends of one of said levers is depressed, the reciprocatory bar connected with the rear end of said lever will be lifted and the corresponding denominational stop will be raised into the path of one of said column stops.
26. In a typewriting machine, the combination of a carriage; a step-by-step feed device for said carriage; character keys and a space key controlling said step-by-step feed device; a tabulator for said carriage comprising a tabulator stop mounted on the carriage; a series of denomination stops movable upward into engagement with said tabulator stop; a series of levers extending from front to back of the machine and each connected with one of said denomination stops; a series of push keys mounted in said space key, each push key having a stem adapted to be pushed out over the forward end of one of said levers; and a carriage release device operated by said space key and said lever.
27. In a typewriting machine, the combination of a carriage; printing instrumentalities; a series of printing keys; a space key extending across the front of the key board; a series of push keys mounted in said space key and having stems adapted to be pressed toward the back of the machine; a series of tabulator stops; and a series of levers controlling said tabulator stops and having their forward ends standing back of said space bar and below said key stems.
28. In a typewriting machine, the combination of a carriage; a space key; a step-by-step feed mechanism controlled by said space key, tabulator mechanism normally disconnected from said space key; and means whereby said space key may be connected with and may operate said tabulator mechanism.
29. In a typewriting machine, the combination of a carriage; a step-by-step feed mechanism therefor; a space key for controlling said step-by-step feed mechanism; a device separate from the feed mechanism and coöperating with a part of said feed mechanism to release the carriage; and a special key co-acting with said device and operative thereon through a depression of the space key.
30. In a key-controlled device, the combination of a plurality of parts to be operated; a member movable by hand, normally

- disconnected from said parts; and keys corresponding to said parts, said keys mounted on said movable member and each adapted when operated to connect the corresponding 5 one of said parts with said movable member so as to be operated by said movable member.
31. In a typewriting machine, the combination of a plurality of tabulator stops; a member movable by hand, normally dis- 10 connected from said stops; and a plurality of keys, one for each of said stops, said keys

mounted on said movable member and each adapted when operated to connect the corresponding stop with said movable member.

Signed at Syracuse, in the county of 15 Onondaga, and State of New York, this 16 day of March A. D. 1905.

CHARLES E. TOMLINSON.
